DESIGN FOR A LADY'S COMBINATION BRASSIÈRE AND TRUNKS

Jules Chase, New York, N. Y.

Application April 25, 1934, Serial No. 51,510

Term of patent 14 years

To all whom it may concern:

Be it known that I, Jules Chase, a citizen of the United States, residing at New York city, in the county of New York and State of New York, have invented a new, original, and ornamental Design for a Lady's Combination Brassière and Trunks, of which the following is a specification, reference being had to the accompanying drawing, forming a part thereof.

Figure 1 is a front elevational view, slightly in

perspective, of a lady's combination brassière and trunks showing my new design.

Figure 2 is a rear elevational view, slightly in perspective, of the same.

I claim:

The ornamental design for a lady's combination brassière and trunks, as shown.

In testimony whereof I have affixed my signature.

JULES CHASE.
